UNITED STATES PATENT OFFICE.

HENRY L. BLODGETT, OF CHICAGO, ILLINOIS.

SASH-PULLEY.

SPECIFICATION forming part of Letters Patent No. 329,006, dated October 27, 1835.

Application filed April 16, 1834. Serial No. 128,053. (No model.)

To all whom it may concern:

Be it known that I, HENRY L. BLODGETT, of Chicago, in the county of Cook and State of Illinois, have invented certain new and useful Improvements in Sash-Pulleys; and I do hereby declare that the following is a full, clear, and exact description thereof, reference being had to the accompanying drawings, and to the letters of reference marked thereon, which form a part of this specification.

This invention relates more particularly to the construction of the shells or cases of sash-pulleys, and has for its objects to lessen the cost of production and to facilitate the application of the pulley to window-frames, and at the same time to insure reliable action of the article when put to use. To these ends the invention consists in the several matters hereinafter set forth, and pointed out in the claims.

The invention is herein shown as embodied in a sash-pulley composed of a longitudinally and vertically divided shell having two relatively small wheels or pulleys proper, one behind the other, by which the desired horizontal distance is obtained between the vertical portions of the sash-cord. This construction enables the case to be made vertically shallow as compared with those having but one wheel or pulley of large enough diameter to give the required distance between the said vertical parts of the cord, and such shallow shell in turn enables the face-plate to be made circular, and at the same time not too wide for admission between the stops or frame-guides for the sash to which a given pulley is suited.

The face-plate being circular, the recess therefor in the window-frame may, of course, be cut by a center-bit, and the labor of applying the "pulley" as a whole to the window is therefore greatly lessened. With reference to the same purpose of facilitating the application of the pulley, the body of the shell is formed with its upper and lower margins or walls externally semi-cylindric, so that after cutting the recess in the frame for the face-plate by means of a center-bit, as above stated, the mortise for the body of the shell may be made by boring two holes, one above the other, of size to conform to the said margins of the shell-body, and cutting out the intervening wood with a chisel. By forming

the circular face-plate of definite size the use of a correspondingly-sized center-bit to cut the recess insures perfect accuracy of fit between the edges of the face-plate and the wood. 55

A feature of the invention herein shown consists in the construction of the shell of metal cast in halves, with not only the holes for the pulley-wheels and joining-rivet, but also slots in the lateral edges of the face-plate for the screws by which the shell is secured to the window-frame. Thus constructed the pulley-shell requires no drilling whatever for any purpose, and the cost of its production or manufacture is greatly reduced. By casting the pulleys with trunnions all hand or machine work is rendered unnecessary in the entire structure, except simply in inserting the rivet which holds the halves of the shell together. 70

In some instances a brass face will be applied to the face-plate after the parts of the shell have been joined, and the front or outer pulley-wheel may be made of brass, while the body of the shell and the rear pulley-wheel 75 may be of iron.

In the accompanying drawings, Figure 1 is a top view. Fig. 2 is a front elevation, and Fig. 3 is a side elevation of the complete device having the shell made in halves. Fig. 4 is a horizontal section on the line xx of Fig. 3. Fig. 5 shows the two parts of the shell detached. Fig. 6 is a section in the line xx of Fig. 3, showing a sheet-metal facing applied to the exposed surface of the face-plate. Fig. 7 is a front view of the facing. 85

A is the shell or case, which, when completed, is oblong in a vertical transverse section, is semi-cylindric on its upper and lower margins, and is provided with a circular face-plate 90 formed of the same piece with the shell or pulley-tube. The shell with the face-plate is cast in halves a and a' , the division being made in a central vertical longitudinal plane, as shown. Each half is therefore of suitable form 95 to "draw" properly in molding. The holes for the pulley-wheel pivots, together with bosses or hubs a^2 , surrounding said holes, are cast in the several parts of the shell, as are also the holes a^3 for the cross-bar or rivet by which 100 the opposite halves of the shell are joined, and the marginal slots a^4 in countersunk form,

as shown, complete and entirely ready to admit the screws by which the shell is secured in the window-frame.

For the purpose of bringing the parts of the shell accurately together in all directions, preparatory to riveting them and of holding them in accurately-opposite relation without dependence upon the rivet or other means, the meeting edges of the shell are cast with interfitting projections D and recesses D'. The projections D are beveled in two directions on their inner and bearing faces, and the notches D' are correspondingly made with beveled or inclined walls, which, while insuring the proper effect in directing the parts accurately together in all directions, also favor the drawing of the patterns for said parts from the sand in molding. Thus constructed the accurate connections of the parts a and a' of the shell by means of a rivet, C, is a work requiring little skill, and one that may be performed very rapidly.

In the circular face-plate of size to enter between the frame-stops of a window calling for a given size of pulley it is necessary to provide screw-holes in the face-plate at the sides thereof, because there is no room at the top and bottom, and to provide such screw-holes in the act of casting I make them in the form of open slots, as indicated, but preferably a little shallower than shown, in order that the screw-heads may extend to the edge of the plate, and thus cover or fill the slot more perfectly.

35 The wheels B are commonly cast with the trunnions b thereon, of proper size and length to fit the holes therefor in the shell, and to extend no more than flush with the outer surface of said shell. By making the hubs a' on the shell, instead of on the wheels, the desired freedom and noiselessness of the pulleys are secured, and at the same time the length of the wearing or bearing surfaces for the trunnions is increased to the maximum.

45 E is a sheet-metal facing, usually of brass, struck up with a marginal flange or flanges, e, to partially or wholly surround the edge of the face-plate, and with screw-holes e' and a central opening, e², coincident with the aperture for the wheel and sash-cord. The edges of the face-plate may be cylindrical, and the flange or flanges e of the facing E may be bent over on the back side of the face-plate, as shown in dotted lines; or the edge of said face-plate may be conical or inwardly tapered toward the rear and the flange e simply con-

tracted about said edge. In case the beveled form of edge is employed, the face-plate may be made to fit the recess cut in the frame therefor very closely. The facing E, whether 60 pressed or cast, may have circular screw-holes, instead of slots, and will thus perfectly hide the outer and unoccupied portion of slots in the face-plate which it covers.

In the case of the face-plate being faced with 65 brass or other ornamental metal facing E, the front or outer pulley-wheel, B, will commonly be of metal corresponding to the facing, while the rear wheel, B', is, like the shell, of cast-iron. The product is thus made ornamental 70 without material increase of cost.

In another application for patent I have described a pulley-shell provided with a circular face-plate, and have also therein illustrated the feature of the circular face plate 75 extending above the upper margin of the tubular part of said shell.

I claim as my invention—

1. A cast-metal sash-pulley shell cast in two lateral halves composed of the body portions 80 a and a' and parts A' of the face-plate, said body portions being cast with mutually-engaging projections and recesses on their meeting edges, and the parts of the face-plate being both cast with a marginal slot at right 85 angles to the plane of division of the shell to receive a holding-screw, which slots are of depth sufficient to admit the screw-heads entirely within the circumference of the face-plate, substantially as shown, and for the purposes set forth.

2. A longitudinally and vertically divided sash-pulley shell and face-plate having its parts cast with mutually-engaging projections, and recesses adapted by themselves alone to 95 bring the said parts into proper coincident position when being put together, and also cast with opposite bossed apertures for the wheel-trunnions, and with opposite holes for the connecting-rivet, and also with marginal 100 countersunk slots in the face-plate portions to admit the holding-screws, in combination with a wheel having its trunnions integral therewith, substantially as shown and described.

In testimony that I claim the foregoing as my invention I affix my signature in presence of two witnesses.

HENRY L. BLODGETT.
